UNITED STATES PATENT OFFICE.

FREDERICK HELFENSTEIN, JR., AND JOHN HELFENSTEIN, OF BISMARCK, NORTH DAKOTA, ASSIGNORS OF ONE-THIRD TO JOHN NATHAN, OF BISMARCK, NORTH DAKOTA.

BOTTLE-DELIVERY DEVICE.

Application filed February 17, 1926. Serial No. 38,808.

This invention relates to bottle carriers and has for its object to provide a milk bottle carrier and self delivery of said bottles.

- 5 Another object of the invention is to provide a milk bottle carrier having means whereby a predetermined number of said bottles may be simultaneously delivered therefrom.
- 10 A still further object of the invention is to provide a bottle carrier having separate compartments for each bottle, and means whereby a predetermined number of said compartments may be simultaneously discharged of the contents.

15 Another object of the invention is to provide a carrier divided into a series of independent compartments and means whereby any desired number of the compartments may be simultaneously discharged of the contents.

20 With the above and such other objects in view, as may hereinafter more fully appear, we have invented the device illustrated in the accompanying drawings, in which:

25 Figure 1, is a side, elevational view of our bottle or package carrier;

Figure 2 is a top, plan view thereof in reversed position;

30 Figure 3 is a bottom plan view of Figure 1, in same relative position;

Figure 4 is a section on line 4—4 of Figure 2;

35 Figure 5 is a section on line 5—5, of Figure 2;

Figure 6 is a detail of a spring control; and

Figure 7 is a detail, perspective view of a delivery control device.

40 Like reference characters indicate like parts, throughout the following specification, and in the several views in the drawings, in which 1 indicates a bottle basket, or carrier, consisting of a frame 2, of sheet aluminum or other metal, (or which may be formed of heavy wire mesh, or any other suitable material), said frame consisting of end walls 2' and 3, and side walls 4 and 5, which are secured together by U-straps 6, 7 and 8. The lower parts 9 and 10 of said side walls being notched out about half an inch, as at a, to receive said straps leaving depending portions 11 and 12 of the frame below said straps, so as to provide a clear-

55 ance space between the lower edges 13, 14, 15 and 16 of the frame members and the cross bars 17, 18, and 19, of the said U-straps to accommodate certain working parts of the device to be mentioned later. There is also provided a longitudinal U-strap 20, 60 mounted similar to the strap 7, but being about a half inch thereabove, leaving an intervening space between said strap 20, and the straps 6, 7 and 8.

65 Pivotedly mounted at the intersection of the strap member 17, and 21, of the strap 20, is a rotatable cross 22, having arms 23, 24, 25 and 26 which normally project transversely of the bottomless cups, or compartments 27, 28, 29, and 30, fixed in the frame, 70 forming supports for the milk bottles 31, or other package carried in said cups.

75 Pivoted at the junction of members 18 and 21, is a V-shaped member 32, the arms 33 and 34 of which seat under cups 35 and 36, and a similar V-shaped member 37, has its arms 38 and 39, seated under cups 40, and 41. Spaced apart cross braces 42 and 43 are located parallel with each U-member 17, 18 and 19, said braces also forming bearings 80 for upright, rotatable rods 44, 45 and 46, the lower ends of which fixedly carry the members 22, 32 and 37, respectively. Coil springs 47 and 48 hold the members 32 and 37 in normal position with their respective 85 arms 33 and 34 and 38 and 39 under the cups 35, 36, 40, and 41, as before stated, while a spring 49 coiled around the rod, or elsewhere suitably located, holds the cross member 22, in its normal position. The upper 90 ends of each rod 44, 45, and 46 is provided with a crank terminal 50, to which is fixed a chain or cable 51, operating over a pulley 52, in the bracket 53, said chain or pulley terminating on the hook 54, of the rod 55, 95 extending slidably through the inverted, U-brace 56, and having a stop 57, to limit its downward movement. The upper end of the rod 55, is provided with an eye through which a finger of the hand supporting the 100 basket, through the medium of the handle 59, may readily engage either eye 58, 58' or 58'' to draw up rod 55, and through the cable 51, rotate the rods 44, 45, or 46, and with them the members 22, 32, or 37, moving their respective arms from under the bottles in the several desired compartments or cups in the basket and releasing the bot-

bles therein, whereby two or four of the bottles or packages contained therein, as the case may be, are allowed to be released from said basket or carrier, 1, said carrier having 5 first been seated upon the stoop or other surface upon which the bottles are to be delivered. Upon the release of the eye 58, the spring control will cause the member 22, 32 or 37, to resume its normal position. Thus, 10 either two or four bottles may be released by a mere movement of the finger saving all the time ordinarily required to pick up the bottles from the basket and set them down again. Approximately one-fourth of the 15 time of delivery is saved in the use of this device.

Having described our invention, that which we claim to be new and desire to procure by Letters Patent is:

- 20 1. In a bottle carrier means for the simultaneous delivery of a plurality of bottles therefrom, said means embracing movable bottom members, said members being rotatable.
- 25 2. In a bottle carrier means for the simultaneous delivery of a plurality of bottles therefrom, said means embracing movable bottom members, said members being rotatable, in a horizontal plane.
- 30 3. In a bottle carrier means for the simultaneous delivery of a plurality of bottles therefrom, said means embracing movable bottom members, said members being rotatable, in a horizontal plane, independent 35 compartments under which said members operate.
- 40 4. A milk bottle delivery device consisting of a carrier having a series of compartments and means whereby the contents thereof may pass through the bottom of said compartments, said means consisting of a movable bottom member, said member being rotatable.
- 45 5. A delivery device consisting of a carrier having a series of compartments, means whereby the contents thereof may pass through the bottom of said compartments, said means consisting of a movable bottom member, said member being rotatable, and 50 means for rotating said member.
- 55 6. A delivery device consisting of a carrier having a series of compartments, means whereby the contents thereof may pass through the bottom of said compartments, said means consisting of a movable bottom member, said member being rotatable, means for rotating said member, and means for holding said member in normal position.
- 60 7. A milk bottle delivery device consisting of a carrier having a series of compartments, means whereby the contents thereof may pass through the bottom of said compartments, said means consisting of a movable bottom member, said member being rotatable, means for rotating said member, 65 and means for holding said member in normal position.

means for holding said member in normal position, and a rod upon which said member is carried.

8. A delivery device consisting of a carrier having a handle and a series of compartments, means whereby the contents thereof may pass through the bottom of said compartments, said means consisting of a movable bottom member, said member being rotatable, means for rotating said member, 70 means for holding said member in normal position, a rod upon which said member is carried, and means for rotating said rod.

9. A delivery device consisting of a carrier having a series of compartments, means 80 whereby the contents thereof may pass through the bottom of said compartments, said means consisting of a movable bottom member, said member being rotatable, means for rotating said member, means for holding said member in normal position, a rod upon which said member is carried, means for rotating said rod, said last means embracing a crank on the rod, and means for 85 operating the crank.

10. A delivery device consisting of a carrier having a series of compartments, means whereby the contents thereof may pass through the bottom of said compartments, said means consisting of a movable bottom member, said member being rotatable, 90 means for rotating said member, means for holding said member in normal position, a rod upon which said member is carried, means for rotating said rod, said last means embracing a crank on the rod, and means for 95 operating the crank, and a cable forming said last means.

11. A delivery device consisting of a carrier having a series of compartments, means 100 whereby the contents thereof may pass through the bottom of said compartments, said means consisting of a movable bottom member, said member being rotatable, means for rotating said member, means for holding said member in normal position, a rod upon which said member is carried, means for rotating said rod, said last means embracing a crank on the rod, means for operating the 105 crank, a cable forming said last means, and a finger control for operating said cable.

12. A delivery device consisting of a carrier having a series of compartments, means whereby the contents thereof may pass through the bottom of said compartments, 110 said means consisting of a movable bottom member, said member being rotatable, means for rotating said member, means for holding said member in normal position, a rod upon which said member is carried, means for rotating said rod, said last means embracing a crank on the rod, and means for 115 operating the crank, a cable forming said last means, a finger control for operating said cable, a pulley over which the cable operates. 120 125 130

13. In a device as described a plurality of compartments open at both ends, and a member having rotatable arms projecting under said compartments. ously removing said arms from under said compartments, and automatic means for replacing said arms in normal position. 30
- 5 14. In a device as described a plurality of compartments open at both ends, and a member having rotatable arms projecting under said compartments, and normally forming a support for the contents thereof. 35
- 10 15. In a device as described a plurality of compartments open at both ends and a member having a rotatable arm projecting under each compartment, and normally forming a support for the contents thereof, means for removing said arms from under said compartments. 40
- 20 16. In a device as described a plurality of compartments open at both ends, a member having arms projecting under each compartment and normally forming a support for the contents thereof, and means for simultaneously removing said arms from under said compartments. 45
- 25 17. In a device as described a plurality of compartments open at both ends, a member having arms projecting under each compartment and normally forming a support for the contents thereof, means for simultane- 50

In testimony whereof we affix our signatures.

FREDERICK HELFENSTEIN, Jr.
JOHN HELFENSTEIN.
